D10-55. OR D 964 EX

N° 964.

Theodore R. Tinby
Design for Barometer Case.
Patented Nov. 10, 1857.

Dec. 964

Theodore R. Timby, of Medina, N.Y.
Letters Patent No. 964, Dated Nov. 10th 1857—

The schedule referred to in these Letters Patent and making part of the same.

To all to whom these presents shall come:—

Be it known that I, Theodore R. Timby, of Medina in the county of Orleans and State of New York, have invented an Improvement in Designs for Barometer Cases, and that the following is a full, clear, and exact description of the principle or character which distinguishes it from all other things before known and of the usual manner of making, modifying and using the same, reference being had to the drawing.

My invention consists in a new design for Barometer cases, the configuration, outline, and external character of which are shown in the drawing; the parts, a, being of metal and part, b, of glass.

What I claim as my invention is the design of Barometer Case as herein set forth.
